UNITED STATES PATENT OFFICE.

EDWARD FREESE, OF NEW YORK, N. Y.

DESIGN FOR AN EGG-TESTER.

SPECIFICATION forming part of Design No. 32,578, dated April 24, 1900.

Application filed March 12, 1900. Serial No. 8,409. Term of patent 3½ years.

To all whom it may concern:

Be it known that I, EDWARD FREESE, a citizen of the United States, residing in the city, county, and State of New York, have invented and produced a new and original Design for Egg-Testers, of which the following is a specification, reference being had to the accompanying drawing, forming part thereof.

The figure is a perspective view of the egg-tester, showing my new design.

As shown in the drawing, the leading or material features of my design are the generally triangular shape, the sunken top with the hole in it, and the tube-like projection on the side.

My invention relates to the general shape

or outline of the egg-tester, and it will be noticed that it is of a generally uniform size from top to bottom and is triangular in cross-section.

Having described my invention, what I claim as new, and desire to secure by Letters Patent, is—

The design for an egg-tester herein shown and described.

In testimony whereof I have signed my name to this specification in the presence of two subscribing witnesses.

EDWARD FREESE.

Witnesses:

FRANK KUGLER,
WARREN B. HUTCHINSON.
